UNITED STATES PATENT OFFICE.

DAVID BROWN, OF LAWRENCE, MASSACHUSETTS.

LOOM-SHUTTLE.

1,229,578.

Specification of Letters Patent. Patented June 12, 1917.

Application filed October 16, 1916. Serial No. 125,842.

To all whom it may concern:

Be it known that I, DAVID BROWN, a citizen of the United States, residing at Lawrence, in the county of Essex and State of Massachusetts, have invented an Improvement in Loom-Shuttles, of which the following is a specification.

This invention relates to that class of loom shuttles, which are adapted to receive the ordinary wooden bobbin, and also the paper-cop-tubes on which thread is frequently wound, when sold in cop form; a cop-tube of this character being made to serve as a bobbin, when the shuttle in which it is used is provided with means for holding it in place on the spindle.

Prior to my invention, shuttles have been produced which are provided with means adapted to secure either the paper cop-tube, or wooden bobbin on the spindle, but, so far as I am aware, these devices have either been expensive to manufacture, or unreliable, in holding the paper bobbin in place.

The object of my invention is to provide a form of shuttle of this character which is adapted to hold either form of bobbin in such a manner that all possibility that the bobbin will become loose on the spindle will be avoided, and which may be made at an expense but slightly in excess of that incurred in making a shuttle adapted to receive a wooden bobbin only.

I accomplish these objects by the means shown in the accompanying drawing, in which:—

Figure 1 is a plan view of a loom shuttle embodying my invention, and showing the parts in position for use.

Fig. 2 is a central longitudinal section thereof.

Fig. 3 is a similar view, showing the spindle swung out of the shuttle, to permit the changing of the bobbin.

Fig. 4 is a cross-sectional view on the line 4—4 of Fig. 1.

Fig. 5 is a view, similar to Fig. 2, and showing a wooden bobbin in position in the shuttle.

In general construction and arrangement, the shuttle illustrated does not substantially differ from various well-known forms of shuttles in general use; the shuttle comprising the wood body *a*, having a spindle *b* mounted in the shank *c*, the latter being mounted on a pivot pin *d*, held in the shuttle body, and adapted to permit the spindle

to be swung to the oblique position of Fig. 3, to permit the bobbin to be changed. The shank *c* has a rigid arm *c'*, which extends from the under side thereof, and at the opposite end thereof from the spindle. A spring *e* is arranged to engage the spindle shank *c* through a follower *f*, to hold it in normal position, said spring permitting outward swinging of the spindle against its action.

According to my invention, two spring fingers *g* and *h* are secured, one on the other, against the under side of the shank arm *c'*, by means of the pin or rivet *i*, which passes therethrough adjacent the ends thereof, the finger *h* being held directly against the arm *c'* and the finger *g* against the under side of the finger *h*. Said fingers are arranged to extend beneath the shank and the base end of the spindle, and are provided with bobbin-engaging toes *g'* and *h'*, respectively, arranged to extend at approximately right angles thereto, toward the spindle, and each having a concave recess in its end corresponding to the curvature of the bobbin which it is to engage, as hereinafter described. The toe *h'* of the spring finger next the spindle shank is arranged to extend toward the spindle near the base of the latter, and the toe *g'* on the finger *g*, is disposed at a short distance therebeyond. A stop pin *j* is mounted in the shuttle body adjacent the front end of the spindle shank, at the side of the pivot thereof next the spindle, and between said shank and the fingers *g* and *h*, the position thereof being such that, when the spindle is lying in its normal position in the shuttle, the spindle shank will lie in close proximity thereto, as indicated in Fig. 1, and, when the spindle is swung upwardly, corresponding upward swinging movement of the free end-portions of the fingers *g* and *h* will be prevented, so that they will practically be drawn away from the spindle as it is lifted. An annular groove *b'* is formed in spindle *b* adjacent its base end, said groove being arranged in such a position that the upturned toe *h'*, of the finger *h*, will engage the spindle in said groove, when the spindle is in its normal position.

X indicates a common form of paper-tube-bobbin which has a tapering bore adapted to receive the spindle *b* and to be placed thereon, so that its base end abuts against the spindle shank *c*. When in position, the tube extends over the annular groove *b'* of the

spindle, so that, when the spindle is swung back into the shuttle, the toe-portion h' will engage the tube directly opposite the annular groove b' , and indent it or press it into said annular groove and clamp the indented portion against the bottom thereof, as shown in Fig. 2, so that the bobbin will be clamped on the spindle much more securely than if ordinary frictional engagement were relied on. The toe h' is, also, so located that, when a wooden bobbin y , is placed on the spindle, the end of its base will be placed against said toe h' , and the bobbin will be held in position to receive the upturned toe g' , in its holding groove, as shown in Fig. 5. It will thus be apparent that either form of bobbin may be securely held in position in the shuttle, in practically the same manner.

The expense of manufacture of a shuttle, such as above described, is but slightly greater than that of the ordinary shuttle of the same type, and less than that of various other devices adapted to receive both kinds of bobbins, which are in use.

In the above-described construction, the provision of independent spring fingers, arranged respectively to engage a paper or a wooden bobbin, also possesses various other advantages, which are of practical importance, particularly as compared with a device in which a single spring is bent to provide means for engaging both the paper and wooden bobbins, for the following reasons:—It is very essential that a strong pressure be applied to the paper bobbin or tube to hold it in place, for it has no groove, in which the spring finger may engage, so that a frictional engagement of some form must be relied on to hold it in place. The diameters of the bases of the wooden bobbins vary to a substantial extent, so that the spring finger must not only be sprung outwardly far enough to permit the bobbin to be placed in position on the spindle, but it is frequently held for long periods in a strained position. A gradual weakening of the spring is thus caused, so that it will soon become weakened to such an extent that it will not grip the paper bobbin or tube with sufficient firmness to hold it securely, although it will securely hold the grooved wooden bobbin, which is not held by frictional engagement, and, therefore, to hold which does not require any particular degree of tension in the holding spring. It is also difficult, as a practical matter, so to form an intermediate portion of a flat spring that it will bite into the paper bobbin or tube to a sufficient extent to hold the latter effectively.

With the arrangement of two independent spring fingers herein described, the excessive strain, which is, or may be placed on the finger which holds the wooden bobbin, in no way affects the finger which holds the

paper bobbin, while the finger which holds the wooden bobbin acts to reinforce the other finger, so that a double spring tension is at all times effective to hold the paper bobbin.

I claim:—

1. A loom shuttle having a pivotally mounted spindle adapted to receive either a wooden bobbin or a paper cop-tube, a pair of fingers supported adjacent the pivoted end of said spindle, one having its end-portion spring-actuated to engage the bobbin base to lock a bobbin on the spindle, and the other having its end-portion spring-actuated to clamp a cop-tube against the spindle, and means to hold said fingers out of their operative positions when the spindle is swung out of the shuttle.

2. A loom shuttle having a pivotally mounted spindle adapted to receive either a wooden bobbin or a paper cop-tube, a pair of spring fingers mounted adjacent the pivoted end of said spindle, one of said fingers being arranged to clamp a cop-tube against the spindle and the other to lock a bobbin on the spindle and to yield independently of the cop-tube clamping finger, and means to force said fingers from their operative positions when the spindle is moved from its normal position.

3. A loom shuttle having a spindle pivotally mounted therein, and adapted to receive either a wooden bobbin or a paper cop-tube, a pair of spring fingers mounted adjacent the pivoted end of said spindle and extending longitudinally thereof, one of said fingers having a catch adapted to engage the base of a bobbin to lock it on the spindle and to be sprung outwardly from the spindle independently of the other finger, and the latter finger having its end portion arranged normally to clamp a cop-tube against the spindle.

4. A loom shuttle having a spindle pivotally mounted therein adapted to receive either a wooden bobbin or a paper cop-tube, a pair of spring fingers fastened one on the other against said spindle adjacent its pivot, the outermost finger extending beyond the innermost and having means at its end to engage and lock a bobbin on the spindle and the innermost finger having means at its end to clamp a cop-tube against the spindle, and means arranged to engage the innermost finger to spring said fingers away from the spindle when the spindle is swung outward from the shuttle.

5. A loom shuttle having a pivotally mounted spindle adapted to receive a wooden bobbin or a paper cop-tube, a pair of fingers mounted adjacent the pivoted end of said spindle with one lying against the other and each having an inturned toe at its end, the outermost of said fingers extending beyond the other and spring actuated

to press its toe into the groove of a bobbin base on the spindle, and the innermost of said fingers being spring actuated to press its toe against a cop-tube on the spindle, to 5 clamp the tube thereagainst, and having the side of its toe arranged to provide a stop for the base end of a wooden bobbin and means to force said fingers away from the spindle when the latter is swung out from 10 the shuttle.

6. In a loom shuttle, a pivotally mounted shank having a spindle carried thereby, a pair of superimposed spring fingers rigidly secured, one on the other, at corresponding 15 ends to said shank, so that the outer finger may act to reinforce the inner finger and may be sprung outwardly independently

thereof, each of said fingers having in-turned, bobbin-engaging projections, with the inner finger having its projection normally extending in clamping engagement with the spindle, and the outer finger with its projection normally disposed to engage in the grooved base of a bobbin on the spindle, and means on the shuttle body to hold 20 25 the free ends of said fingers against outward swinging movement with the spindle.

In testimony whereof, I have signed my name to this specification.

DAVID BROWN.
